UNITED STATES PATENT OFFICE.

RALPH W. HUTCHENS, OF EAU CLAIRE, WISCONSIN, AND STANLEY P. WOODARD, OF NEW YORK, N. Y., ASSIGNEES TO STANWOOD RUBBER COMPANY, OF NEWARK, NEW JERSEY, A CORPORATION OF DELAWARE.

DESIGN FOR A TIRE TREAD OR SIMILAR ARTICLE.

60,927.

Specification for Design.

Patented May 2, 1922.

Application filed December 6, 1919. Serial No. 343,130. Term of patent 3½ years.

To all whom it may concern:

Be it known that we, RALPH W. HUTCHENS and STANLEY P. WOODARD, citizens of the United States, and residing in the city of Eau Claire, in the county of Eau Claire and State of Wisconsin, and in the city of New York, in the borough of Manhattan and State of New York, respectively, have invented a new, original, and ornamental Design for a Tire Tread or Similar Articles, of which the following is the specification, reference being had to the accompanying drawings, forming a part thereof.

In the drawings:

Figure 1 is a fragmentary plan view of a tire tread showing our new design.

Figure 2 is a sectional view taken on line 2—2 of Figure 1.

Figure 3 is a fragmentary sectional view taken on line 3—3 of Figure 1.

We claim:

The ornamental design for a tire tread or similar article, as shown.

RALPH W. HUTCHENS.
